[57] CLAIM

The ornamental design for an infant carrier, as shown and described.

DESCRIPTION

FIG. 1 is a perspective view of an infant carrier showing my new design;

FIG. 2 is a top plan view thereof;

FIG. 3 is a front elevational view thereof;

FIG. 4 is a left side elevational view, the right side elevational view being a mirror image thereof;

FIG. 5 is a rear elevational view thereof; and

FIG. 6 is a bottom plan view thereof.

The characteristic feature of the design resides in the combination of a smoothly curving bottom surface and a pair of spaced-apart, parallel, generally triangular projections extending from the back of the carrier, the outer edges of the generally triangular projections being gently curved.

FIG. 1.

FIG. 2.

FIG. 4.
